UNITED STATES PATENT OFFICE.

GEORGE W. KNIGHT, OF HOPEDALE, MASSACHUSETTS, ASSIGNOR TO GEORGE DRAPER & SONS, OF SAME PLACE.

SPINDLE AND BEARING THEREFOR.

SPECIFICATION forming part of Letters Patent No. 508,323, dated November 7, 1893.

Application filed June 2, 1893. Serial No. 476,333. (No model.)

To all whom it may concern:

Be it known that I, GEORGE W. KNIGHT, of Hopedale, county of Worcester, State of Massachusetts, have invented an Improvement in Spindles and Bearings Therefor, of which the following description, in connection with the accompanying drawings, is a specification, like letters on the drawings representing like parts.

The pintles or lower ends of sleeve whirl spindles commonly enter and rotate in bolster bearings which while free to vibrate to a limited extent in the bolster case, are kept from rotating with the spindle by a pin and slot connection.

In the invention to be herein described a spindle having a sleeve whirl rigidly attached thereto is employed in connection with a rigid bolster or lateral bearing, I being enabled to use such rigid bolster or bearing because I have entered the pintle of the spindle into a shoe, which, besides being interposed between the pintle and bearing is connected loosely by a suitable rivet or equivalent, so that the shoe rotates with the spindle in the bearing at the interior of the supporting-case.

In my invention the spindle does not rotate in the shoe, but it has freedom to tip or move laterally in or with relation to said shoe to a limited extent, the fit between the lower end of the spindle and shoe being preferably looser than between the upper end of the shoe and the pintle. By removing the rivet or equivalent uniting the shoe to the pintle of the spindle, the spindle and shoe may be separated when desired, as when a new shoe is to be applied for a worn one. The shoe may be made of the same or a different metal from that used in the spindle, that is, it may be of any metal thought or found to possess superior properties for bearings, as for instance brass or gun metal, or any of the bronzes.

In my invention the bolster may fit the supporting case or outside support rigidly, suitable oil holes being provided to lead oil to the shoe, but this invention is not limited to holding the bolster solidly in the supporting case, or even to the retention of the bolster as an independent piece.

Figure 1, in elevation and section, represents a spindle with a shoe and suitable bear-

ings, the same embodying one form of my invention. Fig. 2 is a section in the line *x*, Fig. 1; and Fig. 3 shows a modification.

Referring to the drawings, A represents a spindle rail, it containing a supporting case B which may be attached to the rail in any usual manner, as for instance, by a nut B' engaging a thread B² of the supporting case. The spindle C shown in Fig. 1 as having a tapering pintle c has a sleeve whirl C' fixed to the blade of or that part of the spindle which is located above the whirl bobbin adhesively. The pintle enters in Fig. 1 a hole made in a shoe b and preferably there will be looseness between the pintle and the inner bore of the shoe.

The pintle and shoe in this present form of my invention, are shown as connected by a pin on one entering a slot or hole of the other, the pin, in this instance marked d, being carried by the spindle and entering holes d' in the shoe, the object being to connect the shoe and spindle so that the shoe will revolve with the spindle and receive the wear which is commonly borne by the pintle of the spindle. For the best results, the looseness between the pintle of the spindle and the interior of the shoe, of whatever construction, will be sufficient to overcome injurious effects from gyration, owing to high speed of the spindle. The exterior of the shoe will be properly shaped to fit its surrounding lateral support, and where the looseness above referred to occurs between the pintle and the shoe, it is unnecessary to have any looseness between the shoe and its exterior lateral support or bearing, and consequently a rigid support may be used.

In Fig. 1, the outside bearing or lateral support for the shoe is represented as a detachable bolster e, fitted externally rigidly or solidly in the supporting case, but my invention would not be departed from if the lateral bearing for the shoe should be made as an integral part of the supporting case, and I have shown such a modification in Fig. 3.

As represented in Fig. 1, the weight of the spindle and its load is borne by the pin d constituting a loose coupling between the pintle of the spindle and the shoe. This shoe,

preferably made of a different metal than the spindle, as for instance, brass or gun metal, may be readily removed when worn and another one substituted in place of it, thus releasing the spindle entirely from wear, and old spindles having worn pintles may be compounded as shown, and be re-used to advantage by providing them with these detachable shoes.

10 The supporting case has, as represented, an oil hole at f , which leads oil down into the lower portion of the case, the oil contacting with the shoe through suitable oil holes, one of which is shown at f' .

15 In the modification shown in Fig. 3, I have shown the spindle D as having a pintle D' , which is substantially cylindrical, it entering a cylindrical hole in the shoe D^2 .

The shoe b^6 , shown in Fig. 3 fits directly 20 against the interior of the supporting case, and is supported by the coupling pin d^{10} carried by the spindle, and in said figure the step d^{12} is a separate piece from the shoe. The spindle and its connected shoe constitute 25 a compound spindle, wherein the portion subject to wear in running, is made detachable and renewable.

This invention is not limited to the particular construction of the connection between 30 the pintle of the spindle which is to carry the bobbin and the shoe, nor to the particular shape of the pintle or to the interior of the shoe, nor is the invention limited to a shoe of the exact shape shown.

35 Prior to this invention I am aware that a spindle whirl has had extended upwardly from it an oil receiving tube adapted to enter the base of a bobbin, and that a blade adapted to carry a bobbin has entered said tube and been 40 connected therewith above the band receiving portion of the whirl by a pin, a pintle integral with the whirl and not connected with the bobbin carrying portion of the spindle entering a bolster suitably sustained in the sup-

45 porting-case. In such plan the pintle connected with the whirl wears rapidly, whereas in this present invention wear upon the pintle connected with the whirl is completely obviated, and all the wear is put upon the shoe 50 which can be readily detached from the pintle of the spindle without in any way disturbing

the whirl or that part of the spindle to which the whirl is fixed.

In my invention the pull of the band on the spindle is through the whirl fixed to that part 55 of the spindle carrying the bobbin, and not to the shoe as has been heretofore practiced.

Having described my invention, what I claim as new, and desire to secure by Letters Patent, is—

1. A spindle having a sleeve whirl rigidly attached thereto, and adapted by its blade to carry a bobbin adhesively, combined with a supporting case having a lateral bearing, and a shoe connected only to the pintle of said 65 spindle and interposed between the said pintle and the said lateral bearing, the shoe rotating with the spindle, substantially as described.

2. A sleeve whirl spindle adapted to carry 70 a bobbin upon its blade, a supporting case having a lateral bearing extended into the said whirl from its underside, combined with a shoe, and means to connect the spindle and shoe loosely at a point below the band-receiving groove of the whirl, the spindle and shoe rotating together, substantially as described.

3. A sleeve whirl spindle, and a supporting case having a lateral bearing which is extended into the said sleeve whirl from its under side, combined with a shoe into which the pintle of the bobbin-carrying spindle is entered loosely, and with devices to connect the said pintle and shoe loosely, to operate, substantially as described.

4. A sleeve whirl spindle having a rigidly connected pintle, and a supporting-case having a lateral bearing extended into the said whirl from its under side, combined with a shoe connected loosely with the pintle of the spindle, the fit between the extremity of the pintle of the spindle and the shoe being looser than between the upper end of the shoe and the pintle within the sleeve whirl, substantially as described.

In testimony whereof I have signed my name to this specification in the presence of two subscribing witnesses.

G. W. KNIGHT.
